SKELETON STRUCTURE FOR RAILWAY CARS

Fritz Heyner, Hanover, Germany, assignor to
 Franz Kruckenberg and Curt Stedefeld, both of
 Hanover, Germany

Application January 19, 1934, Serial No. 707,377
 In Germany January 17, 1933

18 Claims. (Cl. 105—399)

The invention relates to skeleton structures for railway cars, and more particularly for railway cars intended for very high speeds, and describes a novel three-dimensional latticework for such cars. Similar skeleton structures are described and claimed in my prior application Ser. No. 660,283, filed March 10, 1933, on which Patent No. 2,040,257 was granted May 12, 1936. The three-dimensional latticework of the cars described in said application comprises low main girders disposed in the side walls below the bottom edge of the window surface which extends without interruption over the whole length of the car. The ends of these low main girders are provided with rigid flexure resistant or flexure-proof superstructures between which is fixed a moment resisting or buckling-proof roof or a false bottom below or both simultaneously. The inside and the outside linings enclose the main girders. Stiff cross walls disposed at the ends of this skeleton structure complete this latticework in space. These types of skeleton are particularly advantageous for railway vehicles which can be built without regard being paid to any maximum moving dimensions, special restrictions etc.

When however in the design of modern vehicles, particularly of those intended for high speeds, stream-line shapes, low-weight constructions, low position of center of gravity, etc. are to be taken into consideration, while there are fulfilled all conditions imposed by existing railway installations, administrative prescriptions, dispositions of the platforms, habits of the passengers, etc., it is advantageous not to dispose the low main girders within the side walls. In order to reduce the air resistance, the false bottom of the vehicle is arranged close to the rail heads and the cross section restricted to the indispensable amount. When however the floor of the car is left at the level of the platform top, the doors will be placed in recesses in the side wall of the car, these recesses extending from the car floor deeply into the roof. In this way the main girder would be completely cut asunder in the side wall. When the girders are located in the planes of the side walls, other design requirements render it impossible to offset the main girder downwards.

It is an object of the present invention to obviate these several difficulties by the low main girders being disposed between the car floor and the false bottom of the vehicle and at the same time out of the plane of the side walls. The ends

of the girders carry rigid superstructures which are so connected to the girders as to resist bending, and bars capable of resisting bending and buckling extend between the superstructures. These bars may be structural members of the roof or connected with one another by web members or roof sheets so as to form the upper horizontal bracing of the skeleton of the car. This carrying skeleton is completed by shells or shell-like bodies which below are fastened to the low main girders and on top to the said flexure- and buckling-proof roof bars so as to form the car body proper. The said shells consist of a framing comprising stiff cross frames and longitudinal sections and are lined with sheet metal or another suitable lining material, the cross framings securing the roof bars against buckling, which bars are inserted between the end superstructures connected in a flexure-proof way. On account of the low weight aimed at, the side shells are made of the thinnest sheets and sections available which in the case of sensible deformations of the main girders are liable to buckle and crease.

It is a further object of the present invention to obviate this inconvenience by the length of the lateral shells being limited and the number of the said shells arranged in series being determined in accordance with the degree of deformation likely to arise. In some instances this subdivision of the shells in a lengthwise direction will not yet be sufficient so that deformations should be possible within the shell unit concerned without resulting in creasing or buckling. To this end the lining sheets are fastened at one edge only, preferably on through sections, the other edges of the lining being left movable, while the movable joints are sealed in a suitable manner against the penetration of rain, dirt, etc.

The invention is illustrated diagrammatically and by way of example on the accompanying drawings on which

Figs. 1-3 show the principle of the invention in perspective views,

Figs. 4 and 5 show lateral shells,

Fig. 6 shows in an enlarged scale the construction of a short lateral shell,

Fig. 7 shows details of fastening the lining of said shells,

Figs. 8, 10, 12, 13, 14 show different skeleton structures,

Figs. 9 and 11 lateral shells, suited for skeleton structures as shown in Figs. 8 and 10,

Fig. 15 shows the skeleton of the head of a high speed car,

Fig. 16 shows a special arrangement of the bending-proof superstructure at the ends of the low main girder.

Figs. 1 to 3 show the principle of the construction of a car body designed as above described. By 20 and 21 (Fig. 2) are designated the low main girders which are disposed below the floor and to the ends of which are connected rigidly the superstructures 22, 23, 24 and 25. These superstructures, in this instance, are frames 26, 27, 28 and 29, stiffened against bending and which may, for example, enclose vestibules. Between the top ends of the superstructures 22, 23, 24 and 25 is inserted the roof strip 30, the floor 31 acting as the lower horizontal bracing while the said roof strip 30 is the upper horizontal bracing. By lateral shells, which may extend over the whole length of the car (Fig. 1) or comprise a plurality of short ones behind one another (Fig. 3) this car skeleton is completed to the car body proper. According to the purpose aimed at, these shells can have different shapes and appearances. Figs. 1 and 3 show lateral shells suited for passenger cars, in which 32 is the passenger room with a continuous window surface 33, while 34 and 35 are for example auxiliary rooms, such as cloak room, lavatory, etc.; 36 and 37 may be vestibules or the like. Figs. 4 and 5 show the inside and the outside of lateral shells, for example, for container cars. The side surface of these shells is formed by the posts 38 only which are associated with the cross frame 40 and between which suitable containers 39 may be introduced into the car from the side. The roof strip 30 is secured against buckling by the stiff cross frames 40 being disposed in the side shells which frames are connected to the corresponding verticals 41 of the main girders (Fig. 2), the same as to the roof strip 30 in a moment resisting way.

In order to be as light as possible the lateral shells (Figs. 1, 3, 4 and 5) are made of the thinnest sheets and sections available. Structural members of this class tend to bulging, buckling and creasing in the case of deformations exceeding a definite limit. As the lateral shells are fastened to the carrying skeleton they necessarily partake of the deformations thereof. Whenever the magnitude of these deformations is below the limit referred to, the lateral shells can extend over the whole length of the car body (Fig. 1). Otherwise shorter shells must be disposed side by side, their individual length being that of one or several compartments. Fig. 3 shows such a plurality of shorter shells, the joint 55 of which is designated by 42. The shells consist of a skeleton not stiffened and which comprises frames 40 and bottom and top boom sections 45 and 46 respectively. The lining sheets 43 are connected to the frames 40 and the boom sections 45 and 46. In some instances the sheet clothing must, on account of the deformations of the car skeleton, be given so much freedom of motion, that in spite of these deformations the outside surfaces of the said clothing remain smooth. Fig. 6 shows a lateral shell constructed according to those ideas and for example, having the length of one compartment. 47 and 48 are the lateral cross frames, 49 is the lower boom section and 50 the upper one, 51 and 52 being longitudinal sections which border the window surface 53. The sections 49 and 50, by which the lateral shells are connected to the skeleton, must partake of the contractions and dilations of the members of the skeleton to which they are fastened, where-

contractions and dilations since the changes of length are compensated by the particular construction of the cross frames 47 and 48. The lining sheets 54 are at the sections 51 and 52 rigidly fastened to the framing of the lateral shells without being subject to deformations while the other edges 55 of the sheet are left movable.

Fig. 7 shows a perspective view of a section of such a movable arrangement of the lining sheet as taken at a joint formed by the lining plates and the cross beam 48, Fig. 6, which joint is sealed against the penetration of atmospheric matter. 56 and 57 are the web plates of the cross frame 48 (Fig. 6) which are connected with each other by the sections 58 and 59. The latter are so shaped that the web plates 56 and 57 are allowed to springingly move towards or from each other. So the sections 51 and 52 (Fig. 6) are left without sensible stress or deformation. To these sections are fastened the lining sheets 60, which are at their ends reinforced by sections 61 bent of sheet metal and internally connected with rubber sections 62. These two members are together clamped between the said sections 59 and a strip 63 intended for reinforcing the section. On account of its ribbed shape and sufficient softness the rubber 62 ensures tightness and satisfactory mobility. The sheet strip 63 is fastened from the inside by means of bolts 64.

Figs. 8 and 10 show car skeletons constructed on the same inventive idea, Fig. 8 representing a design suited for compartment cars. In this instance 65 and 66 are again the low girders disposed below the floor 67 and out of the plane of the side walls. At their ends they carry the superstructures 68, 69, 70 and 71 connected therewith in a moment resisting way and engaging between them the horizontal bars 72 and 73. By the frames 74 and suitable struts 75, which are at the same time members of an upper horizontal bracing, the said bars are secured against horizontal buckling. To this skeleton are, for example, applied a plurality of shells, each of the length of one compartment, which with their lateral solid-web frames at the same time form the partitions of the compartments. For better clearness only one of these shells (Fig. 9) is shown as being separated from the skeleton. The other shells are represented in the drawings by their side walls 74 only. The superstructures 68, 69, 70 and 71 preferably enclose the auxiliary rooms.

Fig. 10 shows a car skeleton of the solid-web type. The superstructures 78, 79, 80 and 81 disposed at the ends of the main girders 76 and 77 are closed frames, between which the roof strip 82 is inserted. The solid-web construction of the main girder affords particular advantages for the construction of the side shells. In this case it is readily possible to choose the length of the shells to be connected to the said girder, without regard to a bay division of the main girder, which fact can be of great advantage, for example, in the case of cars having compartments of different lengths according to the particular classes. Fig. 11 shows a shell which is suited for high-capacity cars and attached to the thin girder 76 and the roof strip 82 by means of its moment-resisting cross frame 85. In the drawings the other lateral shells are diagrammatically represented by their cross frames laterally connected to the skeleton while the longitudinal sections and lining sheets are omitted.

For certain types of cars it is advantageous to dispose the main girders as close to the side walls

as possible. Figs. 12 and 13 show constructions of this type, in which 84 and 85 are the main girders. The superstructures 86, 87, 88 and 89 against which bears the buckling-proof roof strip 90, are inclined towards the center line while being duly supported in order that full freedom is left for the design of the lateral shells. In Fig. 13 the main girders 91 and 92 are in an inclined position so that the clearance gage restricted in this place is better utilized. The inclined superstructures 93, 94, 95 and 96, which are stiffened against flexure, are at 97 and 98 connected with each other, and a buckling-proof compressional bar 99 is inserted at these points. The closing of the passenger room as effected by means of shells is diagrammatically represented by the supporting frames 100. For better clearness the longitudinal bearers, the horizontal bracing and the sheet lining are omitted in the drawings.

Fig. 14 shows a further embodiment of the inventive idea. The low main girder 101 is disposed below the floor and the superstructures 102, 103, 104 and 105 thereto connected in a flexure-proof way embrace between them the wings or projections 107, 108, 109 and 110 of the roof portion 106. The rigid supporting frames 111 diagrammatically represent the construction of the clothing arrangement.

Fig. 15 shows how the skeleton of a high-speed vehicle is built up in accordance with the present invention and it represents the front end of a modern stream-line high-speed car. The stream-line is diagrammatically shown by the dotted contour 112, while 113 is the running and driving gear and 114 the engine room. The main girders 116 and 117 disposed below the floor 115 of the passenger room are deflected to extend upwards above the running gear and downwards again below the engine room. In suitable places are connected the flexure resisting superstructures 118 and 119, with which is connected the buckling-resistant roof strip 120. To the end of the cantilever portion of the main girders 116 and 117 respectively projecting beyond the running gear 113, there are connected superstructures 121 and 122 which are likewise stiffened against deforming moments. Between these superstructures and those designated by 118 and 119 is disposed a roof portion 123 subject to tensile stress and which has the same relieving effect on the cantilever portion as the roof portion 120 on the central part of the said main girders. The outside contour of the passenger room is again diagrammatically shown by the stiff frames 124. For better clearness the outside lining is omitted in the drawings.

In some instances it is desirable to bring the superstructures connected to the main girders, out of the plane of the said main girders, for example, in order to allow for a more convenient disposition of the auxiliary rooms. Fig. 16 shows such an arrangement. By 125 and 126 are again designated the main girders which are disposed below the floor 127 and in close proximity to the wheels 128 of the running gear. On both sides of the narrow passage 129, which may lead to another car, there are arranged the auxiliary rooms 130 and 131 which may be used as cloak room, lavatory, service compartment, kitchen etc. The superstructures 132 and 133 being disposed in the plane of the main girders 125 and 126 would result in rather narrow auxiliary rooms or at least interfere with an advantageous disposition thereof. This inconvenience is obviated

when the superstructures 132 and 133 are brought out of the plane of the main girders, for example, by being shifted towards the center line of the car. Every single member of the said superstructures must then be constructed as a flexure-resistant frame bar. When symmetry is admissible, closed frames 134 could be used to advantage. The rigid frames 135 diagrammatically represent the lateral shells attached to the skeleton, and the chain-dotted lines 136 and 137 show stiffening members between the two buckling-resistant roof members 138 which are connected to the superstructures 132 and 133.

I claim:

1. In a railway car having a floor and side walls, main girders below said floor and out of the planes of said side walls, superstructures at the ends of and rigidly connected to said girders to resist flexing thereof, a compression resisting roof member connected between said superstructures, and a plurality of spaced connecting means between said roof member and said girders to reinforce said roof member against deflection, said connecting means being located between said superstructures and bowed outwardly from the planes of said girders to provide a clear space above the floor level of greater width than the spacing of said girders.

2. In a railway car having a floor and side walls, main girders below the floor and out of the planes of the side walls, superstructures erected at the ends of said girders, means connecting said girders and superstructures to resist flexing, a compression resisting bar between said superstructures and forming a member of the roof, means located between said superstructures and connecting the respective girders to said bar, said connecting means being bowed outwardly to provide a clear space above the floor level of greater width than the spacing of the said girders, and shells enclosing the useful space of the car and connected to said girders and said bar.

3. In a railway car having a floor and side walls, main girders below the floor and out of the planes of the side walls, superstructures erected at the ends of said girders, means connecting said girders and superstructures to resist flexing, a plurality of compression resisting bars between said superstructure and forming members of the roof, means located between said superstructures and connecting the respective girders to said bars, said connecting means being bowed outwardly to provide a clear space above the floor level of greater width than the spacing of the said girders, and shells enclosing the useful space of the car and connected to said girders and said bars.

4. In a railway car having a floor and side walls, main girders below the floor and out of the planes of the side walls, superstructures erected at the ends of said girders, means connecting said girders and superstructures to resist flexing, said superstructures each including a pair of longitudinally spaced members, a compression resisting roof including lateral extensions positioned between and connected to the respective pairs of spaced members of said superstructures, an outer sheath defining the outer surface of the car, and a plurality of members cooperating with said girders and roof to support said sheath, said members being bowed outwardly from the planes of said girders.

5. In a railway car having a floor and side walls, main girders below said floor out of the planes of the side walls and inclined towards the longitudinal central plane of the car, superstruc-

- tures at the ends of the girders, means connecting said girders and superstructures to resist flexing, a compression resistant roof means including a bar connected between said superstructures, and shells connected to said girders and bar.
6. The invention as claimed in claim 5, wherein said roof means includes a plurality of bars connected between said superstructures, and means connecting said bars for mutually reinforcing the same.
7. In a railway car having a floor and side walls, main girders disposed below the floor and out of the planes of the side walls within planes inclined towards the longitudinal central plane of the car, superstructures disposed at their ends within the same planes, means to connect the said girders and superstructures in a flexure-resistant way, a pressure-resistant bar inserted between the contacting ends of the said structures and adapted to be a member of the roof, and shells connected to the said girders and the said bar.
8. In a railway car having a floor and side walls, main girders below the floor and out of the planes of the side walls, superstructures disposed at the ends and out of the planes of the said girders, means to connect the said girders and superstructures in a flexure-resistant way, a single pressure-resistant bar between the superstructures at substantially the longitudinal central plane of the car and adapted to be a member of the roof, and shells connected to the said girders and to the said bar.
9. In a railway car having a floor and side walls, main girders below the floor and out of the planes of the side walls, superstructures disposed at the ends and out of the planes of the said girders, means to connect the said girders in a flexure-resistant way, a plurality of pressure-resistant bars inserted between the superstructures and adapted to stiffen one another and to be members of the roof, a plurality of outwardly bowed members connecting the respective girders to the bars adjacent the corresponding outer edges of the car, and shells connected to the said girders and bars.
10. In a railway car having a floor and side walls supported indirectly upon running gear, main girders below the floor and out of the planes of the side walls, extensions of the said girders projecting as cantilevers beyond the running gear, superstructures connected to the girders at suitable points, means to connect the said girders and superstructures in a flexure-resistant way, a pressure-resistant bar inserted between the superstructures and adapted to be a member of the roof, and shells connected to the said girders and to the said bar.
11. In a railway car having a floor and side walls supported indirectly upon running gear, main girders below the floor and out of the planes of the side walls, extensions of the girders projecting as cantilevers beyond the running gear, superstructures connected to the girders at suitable points, means to connect the said girders and superstructures in a flexure-resistant way, pressure-resistant bars inserted between the superstructures and adapted to stiffen one another and to be members of the roof, tensional bars connecting the said bars and the said cantilevers, and shells connected to the said girders and pressure-proof bars.
12. In a railway car having a floor and side walls supported indirectly upon running gear,
- main girders below the floor out of the planes of the side walls, extensions of the said girders projecting as cantilevers beyond the running gear, superstructures connected to the said girders at suitable points and at the ends thereof, means to connect the said girders and superstructures in a flexure-resistant way, a pressure-resistant bar inserted between the superstructures and adapted to be a member of the roof, and shells connected to the said girders and the said bar.
13. In a railway car having a floor and side walls supported indirectly upon running gear, main girders below the floor and out of the planes of the side walls, extensions of the said girders projecting beyond the running gear as cantilevers, superstructures connected to the said girders at suitable points and at the ends thereof, means to connect the said girders and superstructures in a flexure-resistant way, pressure-resistant bars inserted between the superstructures and adapted to stiffen one another and to be members of the roof, and shells connected to the said girders and bars.
14. In a railway car having a floor and side walls, main girders below the floor and out of the planes of the side walls, superstructures connected to the said girders, means to connect the superstructures and girders in a flexure-resistant way, shells enclosing the useful space of the car and extending over the full length thereof, a roof strip inserted between the said superstructures, the shells being connected to the said main girders and to the said roof strip.
15. In a railway car having a floor and side walls, main girders below the floor and out of the plane of the side walls, superstructures connected to the said girders, means to connect the superstructures and girders in a flexure-resistant way, shells comprising a plurality of sheathing members enclosing the useful space of the car so as to extend over the full length thereof and a latice-work to which said sheathing members are slidably attached in the plane of the outer surface of the car, a roof strip inserted between the said superstructures, the sheathing members being connected to the said main girders and to the said roof strip.
16. In a railway car having a floor and side walls, main girders below the floor and out of the planes of the side walls, superstructures connected to the said girders, means to connect the superstructures and girders in a flexure-resistant way, a roof strip inserted between the superstructures, a plurality of laterally open shells enclosing the useful space of the car and arranged side by side, which shells are connected to and directly supported by the said main girders and the said roof strip.
17. In a railway car having a floor and side walls, main girders below floor and out of the planes of the side walls, superstructures connected to the said girders, means to connect the superstructures and girders in a flexure-resistant way, a roof strip inserted between the superstructures, a plurality of laterally closed shells enclosing the useful space of the car and arranged side by side, which shells are connected to and directly supported by the said main girders and the said roof strip.
18. In a railway car having a floor and side walls, main girders below the floor and out of the planes of the side walls, superstructures connected to the said girders, means to connect the superstructures and girders in a flexure-resistant

way, a roof strip inserted between the superstructures, a plurality of outwardly bowed members connecting the respective girders to the corresponding edges of the roofing strip, the outer edges of said members defining the outer surface

of the car, and interchangeable containers for insertion between adjacent bowed members and cooperating therewith to form the outer surface of the car.

FRITZ HEYNER. 5
